UNITED STATES PATENT OFFICE.

HEINRICH BRUNE AND HEINRICH HORST, OF DORTMUND, GERMANY, ASSIGNEES TO
NASSPRESS-GESELLSCHAFT MIT BESCHRÄNKTER HAFTUNG, OF WIESBADEN, GERMANY, A CORPORATION.

PROCESS OF DRYING RAW PEAT AND THE LIKE.

1,143,497.

Specification of Letters Patent. Patented June 15, 1915.

Application filed April 8, 1915. Serial No. 30,041.

To all whom it may concern:

Be it known that we, HEINRICH BRUNE and HEINRICH Horst, both citizens of the Germany Empire, and resident of Dortmund, Germany, have invented new and useful Improvements in the Process of Drying Raw Peat and the like, of which the following is a specification.

The object of the present invention is to provide an improved process for drying raw peat and similar vegetable materials of a fibrous nature by pressure and with the use of drying admixtures.

It is customary to add to the raw peat, or other material to be dried, ashes, sand, gravel, small coke, small peat and the like, but these admixtures have been thoroughly mixed with the material to be dried by means of suitable mixing and kneading apparatus. This has been for the purpose of shortening the time required to press the mixture and for making it possible to remove a greater quantity of moisture from the material to be dried.

We have discovered that the wet material, or the material to be dried, and the admixture need be subjected to pressure for a much shorter interval and the wet material more efficiently deprived of its moisture, if the admixture is not intimately mixed with the material to be dried and if all kneading operations are dispensed with.

According to the present invention, the improved process consists in its preferred form in cutting the material to be dried, such for instance as raw peat, into small particles without crushing or squeezing the fibers thereof, or, in other words, while preserving its fibers in an uncrushed condition. The admixture in a comminuted form is then added to the finely cut raw peat, or vice versa and the two constituents then subjected to pressure to extrude the moisture from the raw peat, care being taken during the pressing operation not to so disturb the particles of either the raw peat or the admixture as to interfere with the formation of the small canals and passages through which the water passes and care being taken to maintain the constituents in a loosely mixed and flocculent condition until the pressing operation.

The invention is illustrated in the accompanying drawing for the purpose of showing one form of apparatus suitable for carrying out the process, but it will be understood that any suitable type of apparatus may be employed.

In the drawing:—Figure 1 is a more or less diagrammatic plan view of the apparatus; and Fig. 2 is a partial sectional view, taken on the line 2—2 of Fig. 1.

The admixture, such for instance as comminuted dry peat, is supplied from a hopper 4 on to an endless belt conveyer 3, the admixture being delivered to the conveyer in a thin layer, as indicated in Fig. 2. The raw peat is delivered to the conveyer 3 in the form of a second layer positioned upon the layer of the dry admixture. This is accomplished by passing the raw peat between suitable cutters 1 and 2, whose purpose is to cut the peat into small particles without crushing its fibers. The cut peat is then discharged directly on to the layer of the dry admixture resting upon the conveyer 3. Due to the fact that the raw peat is delivered on top of the layer of dry material, there is little possibility of the raw peat adhering to the conveyer.

The conveyer 3 moves the two layers of material to a suitable chute 5, the purpose of which is to deliver the raw peat and the admixture to a mixing drum 6 having positioned therein, a conveyer 7. The drum 6 rotates with the conveyer 7, so that the raw peat and the admixture are conveyed through the drum, without crushing the fibers or compressing portions of the mixture. The drum 6 discharges into an elevator 8, which, in turn, discharges into the press 9.

When the raw peat and the dried mixture are pressed, care should be taken that the particles are not so moved as to interfere with the formation of the ducts or passages through which the extruded moisture may pass.

The loosely mixed condition of the raw peat and the admixture permits the interval during which the two are subjected to pressure to be greatly reduced and permits a greater quantity of moisture to be extruded from the wet material than has been

possible with the former processes. Furthermore, a less quantity of admixture is necessary.

When raw peat is treated according to the present process, the resulting product is similar to raw brown coal and is ready for briquetting in the same manner as raw brown coal.

What we claim is:—

- 10 The process of drying raw peat and similar wet materials, which consists in cutting the wet material into small particles while preserving its fibers in an uncrushed condition, adding to the cut wet material a dry 15 comminuted admixture, maintaining the wet material and admixture in a loosely

mixed condition, and then pressing the wet material and admixture, for the purpose described.

That we claim the foregoing as our invention, we have signed our names in presence of two witnesses, this 5th day of January 1915.
